(57) **CLAIM**

The ornamental design for a lifter for a basket of an appliance, as shown and described.

DESCRIPTION

FIG. 1 is a perspective view of a lifter for a basket of an appliance showing our new design.

FIG. 2 is a side view of the lifter for a basket of an appliance.

FIG. 3 is a top view of the lifter for a basket of an appliance.

FIG. 4 is a front view of the lifter for a basket of an appliance.

FIG. 5 is a rear view of the lifter for a basket of an appliance; and,

FIG. 6 is a bottom view of the lifter for a basket of an appliance.

In the drawings, the portions shown in dashed lines depict attachment features that form no part of the claimed design.
